DESIGN FOR A TOOTH BRUSH STERILIZER-HOLDER

Rudolph P. Hockenberger, Toledo, Ohio

Application October 9, 1937, Serial No. 72,099

Term of patent 14 years

To all whom it may concern:

Be it known that I, Rudolph P. Hockenberger, a citizen of the United States of America, residing at Toledo, Lucas County, Ohio, have invented a new, original, and ornamental Design for Tooth Brush Sterilizer-Holders, of which the following is a specification, reference being had to the accompanying drawing, forming part thereof.

Fig. 1 is a side elevational view of a tooth brush sterilizer-holder showing my new design;

Fig. 2 is a front view;

Fig. 3 is a plan view; and

Fig. 4 is a bottom perspective view.

I claim:

The ornamental design for a tooth brush sterilizer-holder substantially as shown.

RUDOLPH P. HOCKENBERGER.
